UNITED STATES PATENT OFFICE

2,133,233

LAUNDRY MACHINE

Walter K. Voss, Davenport, and Nicholas L. Etten, Waterloo, Iowa; said Etten assignor to said Voss

Application April 9, 1932, Serial No. 604,178

62 Claims. (Cl. 68—253)

The invention relates generally to laundry machines and the general aim of the invention is to provide a laundry machine having a maximum safety factor, particularly with respect to a wringer mechanism whereby an operator, throughout every manipulative movement of the machine, is protected against injury.

An object of the invention is to provide a new and improved safety mechanism whereby an operator may stop the machine by any one of a number of possible movements.

Another object is to provide, in a mechanism embodying two opposed pressure members, an electrically operable safety mechanism for relieving the pressure between said members upon the application of a slight amount of force to any one of a number of conveniently located control devices.

Another object is to provide a new and improved means for simultaneously relieving an operating pressure on driven cooperative elements and interrupting the drive to the elements.

A further object is to provide a novel means for relieving an operating pressure on driven cooperative elements when the driving means stops while in driving connection with said elements and for preventing reassembly of the elements as long as the driving connection is established.

Still another object resides in the provision of cooperating elements having optionally controlled driven movement and operating under pressure, in which such pressure can be maintained when the power to the driving connection is interrupted, only if the driving connection is disengaged.

A further object is to provide a novel mechanism embodying combinations of several or all of the operative features expressed in the preceding objects.

A further object is to provide means, such as a pilot light, for indicating a connection of the control circuit with a power line.

Another object of the invention is to provide a new and improved mechanism for creating and maintaining an operative pressure between two relatively movable rolls.

In conjunction with the foregoing object, the invention embodies a novel mechanism wherein the pressure between the rolls may be maintained by means which is not directly subjected to the pressure exerted on the rolls and which, therefore, may always be actuated by a very slight force to relieve said pressure even though an unusual pressure, greatly in excess of nor-

mal operating pressures, is intentionally or accidentally produced between the rolls.

Still another object is to provide, in a wringer embodying separable frame members in which the rolls are journaled and which have a separating movement as pressure on the rolls is relieved, novel means for limiting such relative movement of the frame members to prevent a complete separation as well as to maintain a proper relation of said frame members whereby reassembly of the mechanism is facilitated.

A further object is to provide a novel instantly releasable mechanism for maintaining the pressure on cooperating rolls, which mechanism is capable of being held against release by a substantially constant, relatively small force.

Another object resides in the provision of an interlocking means for releasably holding cooperating wringer rolls under operative pressure which embodies interlocks at each end of the rolls, one interlock being releasable as an incident to the release of the other, which other interlock in turn is operatively maintained by a relatively small holding force amply increased, as by a system of levers, to oppose any operative pressure on the rolls.

Still another object is to provide instantly releasable means for holding wringer rolls under operative pressure which is well adapted for control by electromagnetic means.

A further object is to provide, in a safety release mechanism for relieving pressure on cooperating rolls, a novel means for dissipating such pressure upon operation of the mechanism while preventing a violent relative movement between the rolls and the structure attendant thereto.

In the drawings, Figure 1 is a side elevation of a machine embodying the features of the invention.

Fig. 2 is a vertical, longitudinal sectional view through the wringer mechanism and parts associated therewith.

Fig. 3 is a plan view of the wringer mechanism, the protecting casing of the electrical control mechanism being broken away.

Figs. 4 and 5 are vertical transverse sectional views through the wringer mechanism taken along the lines 4—4 and 5—5, respectively, of Fig. 2.

Fig. 6 is a perspective view of a detail of a switch supporting member.

Fig. 7 is a fragmentary side elevation of the wringer on an enlarged scale.

Machine organization in general

In general, the machine organization which 15 has been selected for the purpose of illustrating the present invention is a washing machine, indicated at 20 (Fig. 1), having a wringer mechanism 21 associated therewith. The preferred driving means is an electric motor 22, supported 20 in a suitable manner beneath the tub 23 of the washing machine and connected with an agitator shaft 24 located within the tub by a conventional type of clutch controlled means which, since it forms no part of the present invention, 25 is not fully described. The motor 22 is also connected, by such means as a gear train (not shown) but located within the casing 25, with a vertically extending wringer drive shaft 26 which extends through a concealing sleeve 27 into a 30 gear box 28. The gear mechanism within said box includes a clutch device, which is of conventional type, and is illustrated in dotted outline at 28^a (Fig. 2). The device is, in this instance, operable by a clutch shaft 29 (Fig. 2) and hand 35 lever 30 to connect one of the rolls of the wringer with the motor driven shaft 26 for rotation in either direction.

The wringer embodies the usual pair of wringer 40 rolls arranged to be placed and normally maintained under pressure by a latching means which 45 may be electromagnetically controlled. Where the electromagnetic control is employed, circuits are utilized for permitting certain operations to be carried on as well as to instantly relieve the pressure between the wringer rolls by releasing the latching means upon the occurrence of any 50 one of a number of manipulations by the operator. The mechanical structure of the wringer and the coordination therewith of an electric control mechanism will be hereinafter more fully described.

The wringer construction

The preferred wringer construction embodies a 55 supporting means comprising two separable sections constituting a frame section 31 and a head section 32. The frame 31 is formed of a horizontal base member 33 and upwardly extending side frame members 34 and 35, the side frame member 34 being shown at the right-hand side 60 of the wringer as illustrated in Fig. 2. The base member 33 (as shown in Fig. 17) comprises an elongated downwardly facing channel-shaped member, the base portion of which at each end is turned upwardly and thence outwardly to provide 65 horizontal bearing supports 36 which are offset with respect to the base. Extensions 37 from both ends of the sides of the base member underlie the bearing supports 36.

The side frame members 34 and 35 are substantially 70 similar and, as shown in Fig. 13, comprise elongated, substantially tubular members having slots 38 extending longitudinally through the inner faces thereof. The lower ends of the side frame members are arranged to be embraced 75 by and are rigidly secured to the extensions 37

on the base 33 with the bearing supports 36 extending through the lower portions of the slots 38. Referring to Fig. 2, the tubular side members 34 and 35 provide channels for slidably receiving lower half-bearings 39 which rest on the bearing supports 36. The frame 31 supports lower and upper wringer rolls 40, 41, respectively, which are fixed on shafts 42, 43, the ends of which extend beyond the ends of the rolls and through the slots 38. The ends of the lower shaft 10 are journalled in the bearings 39, and in the present embodiment one end of the shaft for the lower wringer roll 40, illustrated in Fig. 2 as the left-hand end, has a connection, generally indicated at 44, with the clutch controlled driving mechanism 28^a located within the gear box 28. The upper wringer roll 41 is driven by frictional engagement with the lower wringer roll 40 and the ends of its shaft 43 are journalled in downwardly facing half bearings 45 located within 20 the channels of the side frame members and resting upon the ends of the shaft.

The head section 32 is, in this instance, in the form of an elongated dish-like member arranged to extend between the side frame members and having the ends thereof fashioned to fit telescoped over the upper ends of the side frame members. The extent of such telescoping movement is preferably limited by such means as lugs 46 (Fig. 13) struck outwardly from the sides of 30 the frame members 34, 35. Preferably, the margin of the head is turned outwardly, as at 47 (Fig. 2), to facilitate movement of the head over the ends of the side frame members. Centrally, the head has screw-threaded engagement with 35 a pressure applying screw 48 which extends vertically through the head and within the head is rotatably connected by a suitable collar 49 to an elongated leaf spring 50 which extends substantially the full length of the head into overlying 40 relation to the upper bearings 45.

Latching mechanism

The leaf spring 50 is for the purpose of creating wringing pressure on the lower and upper 45 rolls 40 and 41 through the application of force to the upper bearings 45 and, thence, to the upper wringer roll. Such force can obviously be applied to the upper wringer roll only when the head and frame sections are connected against 50 relative movement, and a novel means is provided for latching the head and frame sections together. In the present embodiment, this means comprises the following arrangement of parts. Pivotedly secured to the head section 32, near 55 opposite ends thereof, are elongated U-shaped latch members 51, 52 which depend from the head into the channels of the side frame members 34, 35, respectively, and are so dimensioned that they extend substantially to the bottoms of the frame 60 members and have the side arms thereof positioned adjacent to the side walls of the side frame members.

In each of the latch members 51 and 52, the upper ends of both arms thereof are provided 65 with elongated longitudinally extending slots 53 in which the ends of transversely extending rollers 54 (Figs. 2, 4 and 5) are slidably and rotatably mounted. These rollers are adapted to engage the upper faces of the upper bearing blocks 45 and 70 to occupy a position between said blocks and the ends of the leaf spring 50. The purpose of the rollers will be hereinafter more fully explained. Preferably, the upper ends of the slots 53 are enlarged to receive bolts 55 or the like which ex- 75

tend therethrough and through the side walls of the head 32 pivotally to secure the head and latch members 51, 52 together.

Means for loosely connecting the upper wringer roll shaft 43 with the latch members 51 and 52 upon upward movement of the head is preferably provided so that such movement will carry the upper wringer roll 41 away from the lower wringer roll 40. To this end, pins 56 supported by and 10 extending transversely between the arms of the latch members 51, 52 are disposed immediately beneath the ends of the upper wringer roll shaft 43.

It should be noted that the base portions of 15 the U-shaped latch members 51, 52 underlie the bearing supports 36 in the channels of the side frame members and that this relationship prevents the head 32 from being withdrawn entirely free of the frame. Moreover, the relationship 20 of the latch members with the side frame members definitely maintains the head and frame sections in proper relationship whereby to facilitate reassembly of the mechanism after any releasing operation.

25 The present interlock between the head and frame sections, of which the latch members 51, 52 are a part, is characterized in that the interlock holds the head and frame sections together regardless of the pressure between the wringer rolls, yet may be so maintained by the application 30 of a relatively small, substantially constant holding force which is independent of and unaffected by the pressure on the wringer rolls. The principal advantage inherent in such a relationship is that the operator, in relieving the 35 pressure between the rolls in an emergency, does not have to trip the mechanism against the force of the pressure on the wringer rolls but is merely required to overcome the relatively small holding force.

40 Describing a preferred means by which this relationship is effected, one of the latching members, in this instance the member 51, which is shown in Fig. 16 and is disposed at the right-hand side of the wringer as illustrated in Fig. 2, has transversely aligned notches 57 formed in the arms to face inwardly of the wringer frame. A transverse latching pin 58 (Figs. 2 and 5) fixed in the sides of the frame member 34 is engaged by the notches when the head section 32 is properly assembled with the frame. It should be 45 noted (see Fig. 2) that when the parts are so arranged, the latching member 51 slopes outwardly of the frame from top to bottom and that the base of the latching member is in abutment with the outer side of the frame member 34 to hold the latch engaged.

40 The bases of the notches 57, against which the pin 58 rests in resisting a separating movement of the head from the frame, have inner flat portions 59, which directly abut the pin 58 when the parts are operatively assembled, and outer curved parts 60 constituting cam surfaces for completing a movement of the latching member 51 out of engagement with the pin 58 upon an initial slight lateral movement of the member 51.

70 The other latching member 52 is so pivoted to the head 32 that it extends through the frame member 35 with one side of the latching member closely adjacent to and, at the bottom of the frame, in engagement with the outer side of the frame member 35. The base 61 of the latch member 52 is, as shown clearly in Fig. 11, 75 wider than the rest of the member and this base

is arranged to be engaged by a catch device 62 mounted on the base member 33.

The catch device (see Fig. 15) is of generally U-shaped cross section arranged to be positioned between the sides of the base member 33 5 and pivotally mounted thereon by such means as a bolt 63 extending through ears 64 on the base member and aligned apertures 65 in the arms of the device. Preferably, the device 62 is centered for proper engagement with the base 10 61 by a washer 62a interposed between one side of the catch device and the base and a spring 62b compressed between the other side of the device and the base. The catch device is provided with a pair of transversely aligned hooks 15 66, the upper faces of which are arcuate to allow the base 61 of the latching member to cam past the hooks. As may be seen in Fig. 2, the parts are arranged so that the effective point of engagement of the catch device and base is 20 arranged almost directly to oppose a separating movement of the latching device by the force of the spring but is slightly off-center so that, if the catch device is not held, the spring force may effect such separating movement. Therefore, 25 the latches are normally insufficient to resist the spring pressure exerted on the rolls.

For maintaining the catch device in engagement with the latching member and thus restrain the latches against the normal tendency 30 thereof toward release, means is provided which is effective to multiply a slight holding force a sufficient number of times to overcome any force which might be exerted by the spring. To this end, an elongated lever 67 (Figs. 2 and 7) has 35 an end part 68 bent at right angles thereto, which end extends through aligned apertures 69 (Fig. 15) in the arms of the catch device. The lever and catch device are rigidly secured together as by making the part 68 and the aperture 40 69 of correspondingly angular cross section. Since the lever is relatively long, it will be evident that, if the holding force is applied at or near the upper end of the lever, the effect of the holding force will be substantially increased. 45

For the purpose of holding the lever, a finger 50 70 (Fig. 7) extends laterally therefrom near the upper end thereof and is provided with an anti-friction roller 71 which is arranged to be engaged by a hook 72 or the like carried by a yieldably movable arm 73. Thus, the yieldable arm 73 may be maintained against movement to release the finger 70 by the application of a relatively small force regardless of the force which is created by the pressure on the wringer rolls. The holding force on the arm 73 may be readily overcome by the operator in moving the lever 67 to break the engagement between the roller 71 and hook 72 and to facilitate movement of 60 the lever a finger piece 74 (Figs. 4 and 7) is provided on the upper end thereof.

The operation of the above described mechanism is as follows, it being considered that the head 32 is latched to the frame 31 as shown in 65 Fig. 2. The operator, by striking the finger piece 74 or otherwise releasing the lever 67 for movement, permits the pressure on the wringer rolls 40 and 41 to break the engagement of the hooks 66 on the catch device 62 with the base 70 61 of the latching member 52 thereby allowing the associated end of the head 32 to move upwardly away from the frame. As the end of the head clears the frame, the head is permitted a slight lateral movement (to the right in 75

Fig. 2), which movement carries the latching member 51 sideways to release the notches 57 from the latching pin 58 and thereby free this end of the head for separating movement with respect to the frame. It will be understood, of course, that this sequence of movement occurs substantially simultaneously so that, upon movement of the lever 67, the head 32 will be instantly released from the frame to relieve the pressure on the wringer rolls.

In operation there is normally a heavy pressure on the wringer rolls, which pressure increases tremendously when an object, such as an accumulation of clothes, enters therebetween. If, while the machine is in this condition, the latching mechanism is tripped, the parts which are separable from the wringer frame proper are apt to be thrown violently therefrom with consequent danger to the operator. Even if the separable parts only move a distance of a few inches, some part of the operator's body is apt to be struck thereby with resulting injury. An important feature of the present device, therefore, is the arrangement by which the impulse given the parts by the released spring tension is so confined that the resultant movement of the separable parts is no greater than is necessary to accomplish the purpose.

As shown clearly in Figs. 2 and 7, the pins 54 which extend transversely between the upper ends of the arms of the latching members 51 and 52 and, in operation are disposed intermediate the upper face of the bearing blocks 45 and the ends of the leaf spring 50, are mounted for sliding movement in the elongated slots 53. The slots are so dimensioned that the lower ends thereof extend downwardly beyond the upper faces of the bearing blocks 45 when the parts are operatively assembled. As much tension as is required may, therefore, be placed on the bearing blocks 45 by the tensioning screw 48 and the upper roll 41 is free to move upwardly away from the lower roll 40 as an article is passed between the rolls. Moreover, this arrangement automatically compensates for differences in the length of the upper bearings and, of more importance, for the wear of the wringer rolls.

When the latching mechanism is tripped to free the latch members 51, 52 for movement, the head 32 and its associated parts are forced upwardly by the force of the spring 50 exerted between the head and the bearing blocks. As this action of the spring occurs, the pins 54 move downwardly in the slots 53 until the lower ends of the slots 55 are engaged, thereby positively preventing further application of spring force to move the head upwardly. It may be said, therefore, that, since the tension on the spring is never completely relieved, the effect of the spring in separating the parts is confined to an initial release of spring tension. Violent movement of the head cannot possibly exceed substantially the distance through which the pins 54 travel in reaching the ends of the slots 53 and the pins constitute means which is shiftable, as the tension applying device is released for force dissipating movement, to limit the tension relieving movement of the device. It should be noted that, while the initial dissipation of spring energy does not of itself result in a separation of the frame members to an appreciable extent, it is effective to unlock the frame members for free movement so that there is no pressure exerted on the rolls and an object therebetween may be easily withdrawn.

To reassemble the mechanism after release, the

pressure applying screw 48 is turned to release the pressure which has been trapped or confined in the spring 50. The end of the head carrying the latching member 51 is fitted telescopically over the corresponding end of the frame and the head moved laterally (to the left in Fig. 2) to effect engagement between the notches 57 and pin 58. The other end of the head is then depressed over the upper end of its corresponding frame member and the lever 67 moved laterally into engagement with the holding arm 73. Operative pressure is then created between the wringer rollers by the screw 48.

In order to prevent movement of the lever 67 into engagement with its holding means, it is desirable to provide a shiftable stop which prevents such movement of the lever when the mechanism is not in position to be latched. To this end, the present construction embodies a stop pin 67^a (Figs. 4 and 7) which is carried by the latch arm next adjacent the lever 67 and projects through an elongated slot 67^b in the side wall of the frame member 35. The arrangement of the pin 67^a and lever 67 is such that the head of the pin 67^a engages the side of the lever 67 to prevent movement thereof toward its holding means in all positions of the head relative to the frame except when the head and frame are properly assembled.

Electric control mechanism

30

While any suitable means may be provided for controlling the holding operation of the arm 73, it is preferred to utilize electrically actuated means for this purpose in order that the lever 67 may be released to trip the latching mechanism upon the occurrence of any one of a number of releasing manipulations. One preferred form of means for obtaining this end is best seen in Figs. 7, 9 and 10 and comprises an electromagnetic device 75 rigidly mounted upon a base 76 which, in this embodiment, is supported upon or is formed as an integral part of the gear box 28. The wringer proper is rigidly supported, as by means of the bracket 71, from the gear box and the parts are so arranged that the finger 70 on the lever 67 extends toward the electromagnet 75.

The yieldable holding arm 73 is rigid with a bar 78 which is mounted for movement on a horizontal pivot 79 supported by the base or a part affixed thereto. This swinging movement of the bar is toward and away from the exposed face of the electromagnetic core 80 and the bar carries an inset piece of magnetic steel 81 in opposition to said face. The bar 78 and inset piece 81 in effect comprise the armature of the electromagnet. The arm 73 extends from the bar 78 in such manner that, when the bar 78 is swung toward the electromagnet by energization thereof, the hook 72 will be moved into holding engagement with the roller 71, and, when the electromagnet is deenergized, swinging movement of the bar 78 releases said engagement. The pivot 79 is so disposed that gravity will induce a movement of the armature away from the electromagnet.

Preferably, the face of the hook 72, which is engaged by the roller 71, is arcuate so that, when the parts are fully engaged, the roller is opposed by an almost flat surface, but only a short relative movement is necessary to place a sharper slope of the surface opposite the roller, whereby any force acting on the lever 67 to withdraw the finger 70 is sufficient to break the engagement. It should be noted that the end of the finger 70

35

40

45

50

55

60

65

66

70

75

extends beyond the roller 71, as at 82, for engagement with the bar 78 whereby movement of the lever 67 to bring the catch device 62 and latching member 52 together is effective to swing the armature toward the electromagnet.

Energization of the electromagnet is effected by a circuit which embodies a plurality of circuit breakers or switches for interrupting the flow of current to the electromagnet. The following identification of these circuit breakers is given, reference being had to Fig. 8 and it being understood that the terminology applied to each circuit breaker is merely for convenience in description. The numeral 83 designates a master switch which controls the energization of the electromagnet. This switch is preferably closed in the movement of the lever 67 to engage the latching mechanism for the wringer rolls. An impact switch 84 is arranged to open the circuit to the electromagnet upon the movement by the operator of certain members to be presently described. A clutch switch 85 is included in the electromagnetic energizing circuit and is so associated with the clutch mechanism that the switch is open when the clutch is in any other than a neutral position. A switch 86 is for the purpose of controlling the operation of the main driving motor 22.

The mechanical structure of each of these switches will be described in order. The master switch 83 is best illustrated in Figs. 3, 7 and 10. The electromagnet 75 immediately above the exposed face of the core 80 carries an insulating block 87 which has a pair of electrically independent, horizontally spaced contact points 88 and 89 mounted thereon. The outer face of the bar 78 carries an insulating block 90 which extends above the upper end of the bar to support a heavy, transversely extending conductor 91 in opposition to the contact points 88 and 89. In mounting the block 80 on the bar 78, it is preferred that limited movement of the block relative to the bar be permitted and to this end the block is secured to the bar by a pair of screws 92, 93 which extend rather loosely through apertures in the block into the bar and the upper one of which has a spring 94 bearing between a washer 95 on the screw and the block normally to force the block toward the bar.

As may be seen in Figs. 7 and 10, the contact points 88, 89 are arranged to engage the conductor 91 before the armature is drawn into close abutment with the face of the core 80 whereby to tilt the block 80 outwardly relative to the bar 78 and place the spring 94 under tension. This relationship serves a dual purpose; first, positively to insure contact between the points 88, 89 and the spanning conductor 91 in order to close the circuit and energize the electromagnet before the armature and electromagnet core become engaged, and, second, to impart a slight force for snapping the armature away from the core the instant the energizing circuit for the electromagnet is broken whereby to effect a quick breaking of the circuit through the switch 83, as well as to provide an initial releasing movement of the element 78.

The construction of the impact switch 84 and the parts associated therewith will now be described, reference being had to Figs. 3, 4, 5 and 9. The base 76 has secured thereto a switch frame 96, the preferred form of which, as shown in Fig. 14, comprises a tubular, generally rectangular member arranged to be secured to the base through apertures 97 with the open sides of

the frame facing horizontally. Each end of the frame on both sides thereof is provided with horizontally aligned notches 98 to receive bars 99 (Figs. 2 and 9) of a suitable insulating material. A headed bolt 100 or the like extends through both bars between the ends of the frame and has a spring 101 bearing between one of the bars and the bolt head 102 for exerting a force normally urging the bars toward each other. Each bar carries an electrical contact 103 arranged for engagement when the bars 99 are in their normal, spring pressed position. The switch is arranged on the base 76 so that the bars have one end thereof positioned adjacent to and pointing toward the wringer. The other or inner ends of the bars are embraced by a centrally apertured plate 104 (Figs. 9 and 12) which is secured to the end of the switch frame 96 and provides a fulcrum for the pivotal movement of either bar in breaking the normal engagement of the contacts 103.

Means is provided on either side of the wringer frame for interrupting a circuit through the contacts 103, which means is arranged for instant actuation by the operator in an emergency. Referring to Figs. 1, 3, 4 and 5, U-shaped members 105 are disposed on opposite sides of the wringer frame with the bases of the members traversing the wringer frame adjacent the top of the upper wringer roll and with the side legs 30 extending downwardly along the side frame members 34, 35. Near the extremities of the legs, the members 105 are pivotally secured, as at 106, to arms 107 which are rigid with the wringer frame. The members 105 will, for convenience, 35 be termed impact bars and it will be seen that the bars are movable toward or away from the wringer frame by a push or pull. Moreover, the impact bars are so arranged with respect to the frame that, should some part of the operator's 40 body become caught between the wringer rolls, the operator can scarcely avoid striking or moving one or the other of the bars.

Preferably, the impact bars 105 are connected by transverse rods 108 so that the impact bars 45 may move as a unit. That bar which is adjacent to the control mechanism has a laterally extending finger 109 (Fig. 9) arranged to be interposed between the projecting ends of the insulated bars 99 on the impact switch 84. In consequence of 50 this arrangement, movement of either impact bar toward or away from the wringer frame will cause the finger 109 to engage one or the other of the bars 99 to break a circuit through the contacts 103. The spring 101, which normally holds 55 the switch bars 99 together, is of ample strength to return the impact bars 105 to their normal position when the actuating pressure thereon is relieved.

The structure of the clutch switch 85 is substantially the same as the structure of the impact switch 84 and embodies a U-shaped frame 110 (Fig. 6) arranged to be secured to the base 76 with one end of the frame adjacent to the clutch actuating shaft 28. The opposite sides 65 of the ends of the frame have notches 111 to receive bars 112, 113 of insulating material which carry switch contacts 114 disposed between the ends of the frame. The insulating bars 112 and 113 are normally urged toward each other by a bolt and spring arrangement, generally indicated 70 115, which is similar to that employed for the same purpose in the impact switch 84. One of the insulated bars, in this instance, the bar 113 extends past the clutch operating shaft 28 and 75

through a notch 116 cut therein. The notch is so arranged that, when the clutch mechanism is in neutral, the notch is fully presented to receive the bar 113, under which circumstances the contacts 114 are in engagement to close a circuit therethrough. Should the clutch operating shaft 29 be rotated in either direction to establish a driving connection for rotating the wringer rolls in one direction or the other, such movement of the shaft cams the insulating member 113 outwardly to break the engagement between the contacts 114 and interrupt the circuit therethrough.

The motor switch 86 is of conventional type embodying two circuit breakers 143 and 149 (Fig. 8) for simultaneously interrupting separate circuits, said circuit breakers being manipulable by means of a finger piece 117 (Figs. 1, 2, 3). The switch 86 is mounted upon the side wall of a casing 118 with the finger piece 117 projecting therefrom for convenient manipulation by the operator. The casing 118 is arranged to enclose the various elements constituting the mechanical parts of the electrical mechanism disposed on the base 76 and is normally secured to the gear box in any suitable manner. The casing is, of course, appropriately apertured to permit the clutch shaft 29 to extend therefrom and to allow the latching finger 70 on the lever 67 and the switch actuating finger 109 on the rod 108 to extend therethrough.

The present structure embodies means, herein shown as being a pilot light 119 (Fig. 2), for indicating a flow of current to the control mechanism, said pilot light being arranged, as will hereinafter become apparent, to be lighted whenever the safety release mechanism is connected with the source of current. For compactness the lamp socket 120 is preferably mounted upon an insulating base 121 which, in turn, is secured to the upper side 122 (Fig. 14) of the impact switch frame 96. The pilot light is visible through a lens 123 (Fig. 2) carried by the casing 118.

With reference to Fig. 1, the driving mechanism for the wringer rolls herein illustrated is of the well-known type wherein the gear box 28 and the wringer carried thereby may be adjusted about the wringer drive shaft 26 as an axis to various operative positions, as determined by a catch 124 pivoted on a part which is stationary with the gear box and engageable with notches 125 in a stationary flange 126. Inasmuch as the electric control mechanism is closely associated with the movable wringer, an insulated cable 126a containing the leads and wires connecting said mechanism with the source of current may be conducted (as shown in Fig. 1) downwardly through the concealing sleeve 27 for the wringer drive shaft to a suitable point on the machine, thus concealing and protecting the cable without interfering with the adjusting movements of the wringer.

Control circuit

In describing the electrical circuits embodied in the present device, particular reference is had to Fig. 8. At some suitable point on the washing machine, as on the base 127 (Fig. 1) thereof, a distributor box 128 is mounted, which box carries one part of a three-point connecting jack 129. The points are designated 130, 131 and 132 (Fig. 8). From two of the points, as points 130, 131, wires 133, 134, respectively, lead to the points of an ordinary plug 135 by which the device may be connected with a power line or other suitable

source of current (not shown). A lead 136 connects one side of the winding for the motor 22 with the source of current through the point 130 and a lead 137 connects the other side of the motor winding with the third point 132. The wires and leads 133, 134, 136 and 137 are connected to the stationary part of the jack 129, while the connections to be presently described are attached to the complementary and movable part thereof, which, for convenience, is not shown in Fig. 8.

From the point 130, a wire 138 extends to one side of the pilot lamp 119, thence through a wire 139 around the lamp and through the energizing winding 140 of the electromagnetic device 75. A lead 141 connects the other side of the winding 140 with one of the contacts 103 on the impact switch 84, the other contact 103 being connected by a lead 142 with one contact of the circuit breaker 143 in the motor switch 86. From the other side of the circuit breaker 143, a wire 144 leads to one of the contact points, as point 88, of the master switch 83. The other contact point 89 of said switch, is connected by a lead 146 with that point 131 on the jack 129 with which the wire 134 from the source of current is connected. A wire 147 extends between the lead 146 and the other side of the pilot lamp 119. The above described circuit controls the energization of the electromagnet.

To complete the motor energizing circuit, a wire 148 connects the point 132 on the jack 129 with the circuit breaker 149 in the motor switch 86 and a wire 150 connects the other side of said circuit breaker 149 with the wire 144. The clutch switch 85 is connected in shunt or parallel with the motor switch 86 by providing a lead 151 between one of the clutch-switch contacts 114 and the lead 142 and a lead 152 between the other one of the switch contacts 114 and the wire 150.

Tracing the various circuits, the circuit for driving the motor 22 is as follows: From the plug 135 current flows through wire 133, point 130, lead 136, winding of the motor 22, lead 137, point 132, wire 148, circuit breaker 149 of motor switch 86, wires 150 and 144, contact point 88, conductor 91, contact point 89, lead 146, point 131 and wire 134 to the plug 135. It will be seen that the motor can only be energized when the motor switch 86 is closed and when the electromagnetic device 75 is energized to hold the conductor 91 in circuit closing contact with points 88, 89. Consequently, upon an interruption of the energizing circuit for the electromagnetic device 75, the motor energizing circuit will be interrupted by the movement of conductor 91 with the armature out of engagement with the points 88, 89. As has been pointed out, such movement of the armature trips the mechanical interlock by which pressure is maintained between the wringer rolls 40, 41 so that the effect of interrupting the energizing circuit of the electromagnetic device is to simultaneously stop the driving motor 22 and relieve the pressure between the wringer rolls.

The energizing circuit for the electromagnetic device is as follows: From the plug 135 through wire 133, point 130, wires 138 and 139, winding 140 of the electromagnet, lead 141, contacts 103 of impact switch 84, lead 142, circuit breaker 143 of motor switch 86, wire 144, contact points 88, 89 and conductor 91, lead 146, point 131 and wire 134 to the plug 135. Thus, the impact switch 84 is connected in series with the winding 140 of the electromagnetic device, with the circuit breaker 143 of the motor switch 86, and with the 7

master switch 83. If the motor switch 86 is open, the energizing circuit through the electromagnetic device may be completed through lead 151 from lead 142, contacts 114 of clutch switch 85, lead 152, and wire 150 to wire 144 and thence through the master switch 83 to the source of current as before.

In describing the operation of the present device, it will be considered that the electromagnetic device is energized whereby to hold the master switch 83 closed and the mechanical release mechanism of the wringer against releasing movement. Obviously, since the mechanical release mechanism is so held only when the electromagnetic device is energized, any interruption of current flow to the electromagnetic device, as by blowing a fuse, breaking the circuit of the main power line, breaking the circuit from the power line by disconnecting the plug 135 or jack 129, will be effective to trip the mechanical release mechanism and relieve the pressure between the wringer rolls. Consequently, the wringer rolls can only be maintained in operative condition with pressure exerted therebetween when the washing machine as a whole is properly connected with the source of current.

If, while the mechanism is so connected, either one of the impact bars 105 is moved in either direction, the contacts 103 of the impact switch 84 are separated to break the circuit therethrough and, since the impact switch 84 is connected in series with the winding of the electromagnetic device 75, the energizing circuit therefor is broken to open switch 83, stop the motor and relieve the pressure between the wringer rolls. When the device is in operative condition, the motor switch 86 may be manipulated to break the circuits therethrough and stop the motor. Such manipulation of the switch 86 does not result in deenergization of the electromagnetic device as long as the clutch switch 85 is closed, since the clutch switch is included in a parallel circuit around the motor switch 86. However, it has been pointed out that the clutch switch 85 is closed only when the clutch mechanism within the gear box 28 is in the neutral position thereof. Hence, if the motor switch 86 is manipulated while the clutch mechanism drivingly connects the wringer rolls with the source of power, such manipulation is effective to interrupt the circuit through the electromagnetic device and release the trip mechanism. The same result follows from manipulation of the clutch shaft 29 in either direction from a neutral position while the motor is idle. In either event, the mechanism cannot be reassembled as long as the clutch switch is open.

Should the operator strike the finger piece 14 on the lever 61, the roller 71 will cam past the holding face of the hook 72 and thereby open the master switch 83 to break the circuits through the electromagnetic device and the motor, and at the same time relieve the pressure between the rolls.

The circuit through the pilot light 119 is established whenever the control circuit is properly energized with the source of current, since the light is connected across the wire 138 and lead 146 which are in direct connection with the source of current through the jack 129.

From the foregoing, it will be apparent that a novel mechanism has been provided in which every consideration is given to the safety of the operator. Pressure cannot be created between the wringer rolls as long as the machine is dis-

connected from a source of power and such connection is immediately and permanently indicated by means of a pilot light. When the mechanism has once been set for operation, a relatively slight movement of one of the impact bars 105 in either direction or movement of the lever 61 is immediately effective to relieve the pressure between the wringer rolls and to stop the driving motor. If, while the mechanism is set, the operator wishes to discontinue the motor drive, he may do so by manipulating the motor switch 86 providing the wringer rolls are not then drivingly engaged through the clutch mechanism with the power shaft. Even if the motor is idle while the mechanism is set, movement of the impact bars 105 or the lever 61, or manipulation of the clutch shaft 29 out of neutral position will relieve pressure between the wringer rolls. In effect, therefore, each of the above features contributes toward the inherent safety of the present mechanism.

In addition, the mechanism embodies means whereby the entire force of the pressure on the wringer rolls can never be exerted between the separable parts of the mechanism but instead only an initial part is employed to release the parts for further and unforced separation. This feature eliminates the possibility of injury to an operator by moving parts when the release mechanism is tripped.

We claim as our invention:

1. In a wringer, the combination of a frame having rolls mounted therein, means for holding said rolls in contiguous position, means including an electromagnet for controlling the holding means, a single instrumentality mounted for movement in opposite directions, and means operable by said instrumentality upon movement thereof in either direction to interrupt the circuit to said electromagnet whereby the roll holding means is released to free the rolls for separating movement.

2. In a wringer, the combination of a frame having rolls mounted therein, means for latching said rolls in contiguous position, electromagnetic means for controlling the latching means, and means including a member associated with the frame and capable of being pulled away from said frame by the operator to interrupt the circuit to said electromagnetic means.

3. In a wringer, the combination of a frame having rolls mounted therein, an electric circuit including an electromagnet and a circuit breaker, means including a device adapted to be attracted and held by said electromagnet when energized for holding said rolls in contiguous position, and means mounted adjacent to the rolls for movement toward and away from the frame for actuating said circuit breaker upon such movement in either direction.

4. In a wringer, the combination of a frame having rolls mounted therein, releasable means for holding said rolls in operative relation, means for driving said rolls including a clutch device, and means operatively controlled by said clutch device for rendering the roll holding means ineffective when the clutch device is thrown into engagement while the power of said driving means is disconnected.

5. In a wringer, the combination of a frame having rolls mounted therein, means including electromagnetic means for holding the rolls in operative relation when said electromagnetic means is energized, means for driving the rolls including an electric motor and a clutch, and

- means for breaking the circuits to the electromagnetic means and motor either when the clutch is moved into engagement while the motor is idle or when the motor is shut off while the clutch is engaged.
6. In a wringer, the combination of a pair of rolls arranged to move toward and away from each other, means for maintaining said rolls in contiguous relation, means for driving said rolls including an electric motor and a connecting clutch, a switch for controlling motor operation, and means controlling said first mentioned means to effect release of said rolls for separating movement upon any actuation of said switch when said clutch is in other than a neutral position.
7. In a wringer, the combination of a pair of rolls arranged to move toward and away from each other, means for maintaining said rolls in operative relation, means for driving said rolls including an electric motor and a connecting clutch, a switch for controlling motor operation, and means controlling said first mentioned means to prevent assembly of said rolls into operative relation when said clutch is engaged while said switch is open.
8. An electrically operated safety release mechanism for wringers or the like having relatively shiftable members, and releasable means for holding said members in operative relation comprising, in combination, an electromagnetic device for controlling the holding operation of said releasable means, a circuit including a switch and said electromagnetic device, and means supported adjacent to the shiftable members for reciprocatory movement and operable upon movement in either direction to open said switch.
9. An electrically operated safety release mechanism for wringers or the like having relatively shiftable members and releasable means for holding said members in operative relation comprising, in combination, an electromagnetic device for controlling the holding operation of said releasable means, a circuit for energizing said electromagnetic device including a plurality of circuit breakers, and means operable in an emergency for opening the circuit by one or another of said circuit breakers.
10. An electrically operated safety release mechanism for wringers or the like having relatively shiftable members and releasable means for holding said members in operative relation comprising, in combination, an electromagnetic device for controlling the holding operation of said releasable means, a driving motor, a main control switch, a normally closed switch, and a circuit including said switches and said electromagnetic device, said normally closed switch being connected in series with said electromagnetic device and in parallel with said main control switch and motor, and said main control switch being connected in series with said motor whereby the main control switch may be actuated without deenergizing said electromagnetic device and said device will be deenergized whenever both switches are open.
11. A safety device for mechanism having two relatively shiftable members one of which is a roll, releasable means for holding said members in operative relation, and means for driving the roll, comprising, in combination, an electrically operated device for maintaining said means against release, a control switch, a second switch, a circuit including said switches and said device, and means for opening the circuit through said second switch when the roll is driven.
12. A safety device for mechanism having two relatively shiftable members one of which is a roll, releasable means for holding said members in operative relation, and means for driving the roll comprising, in combination, an electrically operated device for maintaining said releasable means against release, a control switch, a second switch, a circuit including said device and said control switch, a shunt circuit around said control switch and including said second switch, and means for opening said second switch when the roll is connected with the means for driving same.
13. A safety device for mechanism having two relatively shiftable members one of which is a roll, releasable means for holding said members in operative relation, an electric motor for driving the roll comprising, in combination, an electrically operated device for maintaining said means against release, a control switch, a second switch, a circuit including said control switch and motor, a second circuit including said device and said second switch and connected in parallel with said control switch, and means for opening said second switch when the roll is drivingly connected with the motor whereby the circuit through the control switch may be broken without interrupting a circuit through said device only when the motor is drivingly disconnected from said roll.
14. A safety device for mechanism having two relatively shiftable members one of which is a roll, releasable means for holding said members in operative relation, and an electric motor for driving said roll comprising, in combination, an electrically actuated means for maintaining said means against release, a motor circuit adapted to be closed only when the holding means is so maintained against release, and a pair of normally closed circuit breakers interposed in the energizing circuit for said electrically actuated means, one of said circuit breakers being connected to deenergize said electrically actuated means whenever said circuit breaker is opened, and the other of said circuit breakers being connected to deenergize said electrically actuated means only if said roll is drivingly connected with said motor.
15. A safety device for mechanism having two relatively shiftable members one of which is a roll, releasable means for holding said members in operative relation, and an electric motor for driving said roll comprising, in combination, an electrically actuated means for maintaining said means against release, a motor circuit adapted to be closed only when the holding means is so maintained against release, and a pair of normally closed circuit breakers interposed in the energizing circuit for said electrically actuated means, one of said circuit breakers being connected to deenergize said electrically actuated means whenever said circuit breaker is opened, and the other of said circuit breakers being connected to deenergize said electrically actuated means only if said roll is drivingly connected with said motor, and means for independently interrupting motor operation when both of said circuit breakers are closed.
16. In a wringer mechanism, the combination of wringer rolls, means for releasably maintaining said rolls in operative relation including electrically operable safety release mechanism for releasing said rolls for separating movement and a control circuit for said mechanism, and a shunt circuit across said control circuit including a pilot

lamp for indicating connection of the control circuit with a source of current.

17. A wringer comprising, in combination, a wringer frame having separable complementary sections adapted for correlation to provide an open faced enclosure for wringer rolls, rolls mounted in the frame for movement toward and away from each other, means for applying operative pressure to said rolls only when the frame sections are correlated, and electromagnetically controlled means for holding said frame sections correlated.

18. A wringer comprising, in combination, a wringer frame having separable sections, rolls mounted in the frame for movement toward and away from each other, releasable latching mechanism for operatively connecting said separable sections, and an electromagnetic device for maintaining said latching mechanism in operative condition.

19. A wringer comprising, in combination, a wringer frame having separable sections, a pair of wringer rolls mounted in the frame, one of said rolls being movable with one of said separable sections, means for latching said sections together to maintain the rolls in cooperative relationship, and an electromagnetic device arranged when energized to maintain the latching means operative.

20. A wringer comprising in combination, a wringer frame having separable sections, a pair of wringer rolls mounted in the frame, means for creating pressure between the rolls, means for latching said sections operatively together to maintain the rolls in cooperative relationship, and an electromagnetic device acting when energized to maintain the latching means operative, said pressure creating means being instantly affective to release the latching means upon de- energization of the electromagnetic device.

21. In a wringer, the combination of separable frame sections having cooperating wringer rolls therein, means for creating pressure on the rolls, latches for maintaining said sections in operative relation against the separating force exerted by the pressure on the rolls, said latches being incapable alone of so maintaining said sections, and means for holding the latches against release, the latches and the holding means therefor including a leverage system arranged to increase the effective force exerted by the holding means in opposition to the pressure on the rolls, whereby a small force which may be easily overcome by a relatively light touch on the operator's part is ample to hold the latches against release.

22. A wringer comprising, in combination, a frame member having channeled side members, a head fitting over said members, wringer rolls having shafts extending into the channels in said side members, bearings in the channels for said shafts, U-shaped latching members supported by the head to depend into the channels in embracing relation to the corresponding bearings and shafts, means providing a latching interengagement between one of the latching members and the frame upon lateral movement of the head relative to the frame, a pivoted catch device on the frame member movable to engage the other latching member, a lever disposed exteriorly of said frame, and connected with said catch device for moving same, and means releasably engaging said lever to hold the catch device in engagement with the last mentioned latching member.

23. A wringer comprising, in combination, a

frame member having channeled side members, a head fitting over said members, wringer rolls having shafts extending into the channels in said side members, bearings in the channels for said shafts, U-shaped latching members supported by the head to depend into the channels in embracing relation to the associated bearings and shafts, means providing a latching interengagement between one of the latching members and the frame upon lateral movement of the head relative to the frame, a catch device on the frame movable to engage the other latch member, a lever connected with said catch device for moving same, means releasably holding said lever to maintain the catch device in engagement with the latch, and means on the frame normally spaced from the base portions of the latches but engageable thereby to limit the extent of separating movement of the head from the frame.

24. In a wringer, the combination of a frame, cooperating wringer rolls mounted in said frame, means for latching said rolls in operative relation including a member extending along one side of said frame and movable in one direction to release the latching means and in another direction to effect engagement of the latching means, and an electromagnetic device having an armature movable relative thereto and arranged to maintain said member in position to effect engagement of the latching means.

25. In a wringer, the combination of cooperating wringer rolls, means for latching said rolls in operative relation including a member movable in one direction to release the latching means and in another direction to effect engagement of the latching means, and an electromagnetic device having an armature movable relative thereto and arranged to hold said member in position to effect engagement of the latching means, said member having a part engageable with said armature in the movement of the member into such position to move the armature toward the electromagnetic device.

26. In a wringer, the combination of a pair of cooperating rolls, means for latching said rolls in operative position including a movable controlling member, an electromagnetic device for holding said controlling member in position to latch said rolls including an armature holding said member when the electromagnetic device is energized, and a circuit for energizing said device including a switch operable to close the circuit as the armature moves toward engagement with its magnet.

27. In a wringer, the combination of a pair of cooperating rolls, means for latching said rolls in operative position including a movable controlling member, an electromagnetic device for holding said controlling member in position to latch said rolls including an armature engaging said member when the electromagnetic device is energized, said armature being engageable by said member as the member is moved to effect latching of the rolls and movable thereby toward the electromagnet, and an energizing circuit for the device including a circuit breaker operatively connected with said armature to be closed prior to engagement of the armature with the electromagnet.

28. In a wringer, the combination of a pair of cooperating rolls, means for latching said rolls in operative position including a movable controlling member, and means for holding said controlling member against movement into a latch-

ing position when the rolls are out of their co-operative relation.

29. In a wringer, the combination of a frame and a head movable relatively to separate, co-operating upper and lower rolls having shafts mounted in the frame, bearings for supporting said shafts, a leaf spring carried by the head with the ends thereof overlying the bearings for the upper roll, means for tensioning the spring, U-shaped latch members carried by the head and extending into the frame, cooperating means carried by the frame for engagement with the latch members to unite the head and frame, and pins carried by the latch members and disposed intermediate the ends of the spring and the upper bearings to transmit the force of the spring to the bearings and thereby create pressure between the rolls, said latch members having slots therein in which said pins are mounted for limited movement with one end of each slot normally extending beyond the bearing face engaged by the associated pin, whereby when the latched connection is tripped the separating impulse imparted to the head by the spring thrust against the bearings is confined to the extent of movement of the pins into engagement with the ends of the slots.

30. In a wringer, the combination of a frame having cooperating rolls journaled therein, a head mounted on said frame and having a pressure applying means for the rolls mounted therein, means for latching said head and frame together, devices carried by the head for limited shifting movement relative thereto and so disposed as to transmit pressure from said applying means to said rolls, and means for unlatching the head for movement relative to said frame by the released force of said pressure applying means, said devices being shiftable thereby to one limit of movement whereby substantially to confine the expended force of the pressure applying means.

31. A clothes wringer comprising a sectional frame having therein wringer rolls, and spring means for exerting pressure on the rolls, means housed within frame sections for latching said frame sections together to maintain said spring means under pressure, the last mentioned means being normally incapable by itself of resisting the spring pressure, and electromagnetic means for holding said last mentioned means in operative condition.

32. In a mechanism having cooperating pressure elements mounted for movement toward and away from each other, the combination of means including a spring for releasably maintaining said elements in coacting relation under spring pressure, and means acting upon release of the first mentioned means to limit the relief of energy stored in said spring, the last mentioned means comprising devices acting normally to transmit the force of said spring to said pressure elements, said devices having a limited range of movement so as to confine the action of said spring.

33. A clothes wringer comprising, in combination, a frame having relatively movable sections, wringer rolls journaled in bearings in said frame, means including a spring mounted in one section for applying pressure to the rolls through one pair of said bearings, releasable means for locking said frame sections together, and means for limiting the relief of tension on said spring when said locking means is released comprising shiftable elements which transmit pressure from said spring to said bearings, and

stops for limiting the shifting movement of said elements when said locking means is released.

34. In a wringer having a frame and spring means for exerting pressure upon the wringer rolls, latch means for releasably maintaining said spring means in pressure applying condition including a member pivotally mounted within said frame, said latch means being normally insufficient to resist the pressure exerted by the spring means, and holding mechanism engageable with said member to restrain said latch means against movement by said spring means.

35. A wringer comprising, in combination, a frame having rolls mounted therein, pressure applying means for exerting an operating pressure on said rolls, quick release means within said frame for maintaining said pressure applying means in operative condition including a member located externally of said frame, said quick release means being normally incapable by itself of resisting exerted operating pressure, and means detachably engaging said member to releasably hold said quick release means in operative condition.

36. A wringer comprising, in combination, a frame having rolls mounted therein, pressure applying means for exerting an operating pressure on said rolls, quick release means within said frame for maintaining said pressure applying means in operative condition, said quick release means being normally incapable by itself of resisting exerted operating pressure, and means having a releasable connection with said quick release means for holding said quick release means in operative condition when connected and for releasing said quick release means upon disconnection.

37. In a wringer, the combination of a frame having rolls mounted therein, means including an electromagnetic means for holding the rolls in operative relation when said electromagnetic means is energized, means for driving the rolls including an electric motor and a disengageable power transmission, a make and break circuit controlling motor operation independently of said electromagnetic means, a shunt circuit around said make and break circuit for controlling energization of said electromagnetic means, and means for opening said shunt circuit when said power transmission is engaged.

38. In a wringer, the combination of rotatable wringer rolls, means for driving the rolls including an electric motor and a clutch mechanism, and means controlled by said clutch mechanism for making and breaking a motor circuit.

39. In a wringer, the combination of rotatable wringer rolls, means for holding said rolls in operative relation including electrically operated mechanism controlling the holding means, means for driving the rolls including an electric motor and a clutch mechanism, and means controlled by said clutch mechanism for making and breaking a circuit for said motor and said electrically operated mechanism.

40. In a wringer, the combination of wringer rolls, electrically controlled mechanism for holding said rolls under an operating pressure, driving means for said rolls including a manipulable clutch device, and means controlled by said clutch device for making and breaking a circuit for said electrically controlled mechanism.

41. In a wringer, the combination of rotatable wringer rolls, electrically operated mechanism for maintaining said rolls under operative pressure, driving means for rotating said rolls including an

electric motor, a circuit controlling the action of said electrically operated mechanism and said motor and arranged to release pressure on the rolls and stop the motor when the circuit is broken, 5 and a manipulable shunt circuit for independently controlling the action of said motor.

42. A wringer comprising, in combination, a frame having channeled side members, a head supported on said members, wringer rolls having shafts extending into the channels in said side members, bearings in the channels for said shafts, means for detachably securing one end of said head to a corresponding side member, a U-shaped latching member supported by the other end of 15 said head to depend into the channel of its associated side member in embracing relation to the corresponding bearings and shafts, a catch device on the frame member movable to engage said latching member, and means detachably engaging 20 said catch device for holding said catch device engaged with said latching member.

43. A wringer comprising, in combination, a frame having wringer rolls therein, a head supported by said frame, means for detachably securing one end of said head to said frame, a latching member for securing the other end of 25 said head to said frame, a catch device on the frame movable to engage said latching member, a lever connected with said said catch device for 30 movement therewith, and means releasably engaging said lever to hold the catch device in engagement with said latching member.

44. In a wringer, the combination of rolls, a releasable means associated therewith for normally maintaining the rolls in a cooperating relationship and releasable to free the rolls for movement out of such relationship, including a member arranged to be moved by the operator to effect such release of the rollers, a driving 35 motor, a control circuit for said motor, a circuit breaker in said circuit and connected with said member for conjoint actuation, and mechanical means rendered operable upon release of said 40 rolls for positively preventing reestablishment of said circuit as long as the rolls are out of said 45 cooperating relationship.

45. A wringer comprising, in combination, a set of rotary wringer rolls mounted for separating movement, means by which said rolls are 50 releasably held in operative relation under spring pressure, and means for releasing said holding means to permit separation of said rolls, including a pair of release bars at opposite sides of the wringer, each of said bars having a horizontal portion extending along the rolls and two vertical portions positioned adjacent the ends of the rolls and extending through a horizontal plane passing between the rolls.

46. A wringer comprising, in combination, a set 55 of rotary wringer rolls mounted for separating movement, means by which said rolls are releasably held in operative relation under spring pressure, and means for releasing said holding means to permit separation of said rolls, including 60 an impact member extending lengthwise of and adjacent to the rolls, and two impact members extending crosswise of the rolls adjacent to the ends of the latter.

47. A wringer comprising, in combination, a set 65 of rotary wringer rolls mounted for separating movement, means by which said rolls are releasably held in operative relation under spring pressure, and means for releasing said holding means to permit separation of said rolls, including 70 a horizontal impact member extending longi-

tudinally in front of and adjacent to the upper roll, and two vertical impact members extending crosswise of and adjacent to the ends of said rolls, said vertical members passing through a horizontal plane which is located between said 5 rolls.

48. A wringer comprising, in combination, a set of rotary wringer rolls mounted for separating movement, means by which said rolls are releasably held in operative relation under spring 10 pressure, and means for releasing said holding means to permit separation of said rolls, including a pair of bail-shaped impact bars at opposite sides of the wringer and a pair of links located at the ends of the wringer and connecting the impact bars together for simultaneous movement, the intermediate portion of each of said bars extending horizontally in front of the upper wringer roll, and the end portions of each bar extending downwardly from said intermediate 15 portion through a horizontal plane passing between said rolls, said end portions being pivoted 20 at their lower ends to the wringer structure.

49. A wringer comprising, in combination, a set of rotary wringer rolls mounted for separating movement, means by which said rolls are releasably held in operative relation under spring 25 pressure, and means for releasing said holding means to permit separation of said rolls, including a pair of release bars at opposite sides of 30 the wringer, each of said bars having vertical portions positioned adjacent the ends of the rolls and extending through a horizontal plane passing between the rolls.

50. A wringer comprising, in combination, a set of rotary wringer rolls mounted for separating movement, means by which said rolls are releasably held in operative relation under spring 35 pressure, and means for releasing said holding means to permit separation of said rolls, including 40 means to be moved by the operator extending crosswise of the rolls adjacent to the ends and across the bite of the latter.

51. A wringer comprising, in combination, a set of rotary wringer rolls mounted for separating movement, means by which said rolls are 45 releasably held in operative relation under spring pressure, and means for releasing said holding means to permit separation of said rolls, including a pair of bail-shaped impact bars at opposite 50 sides of the wringer, a pair of links located at the ends of the wringer and connecting the impact bars together for simultaneous movement, the intermediate portion of each of said bars extending horizontally in front of the upper wringer 55 roll, and the end portions of each bar extending downwardly from said intermediate portion through a horizontal plane passing between said rolls, and means for movably supporting the connected impact bars in the aforesaid relation to 60 the wringer structure.

52. In a wringer, the combination of a pair of rolls supported for relative shifting movement, unstable latching means at each end of the rolls for holding said rolls in cooperating relation, 65 said latching means being incapable alone of so holding the rolls, and manipulable means having a releasable engagement with one of said unstable latching means to maintain it positively in roll holding condition, the other of said unstable 70 latching means being thereby maintained against disengagement.

53. In a wringer, the combination of wringer rolls supported for relative movement toward and away from each other, quickly releasable 75

- means for maintaining said rolls in close cooperative wringing relation including a part movable back and forth as said means is released and reset, and stop means movable as said quickly releasable means is released into the path of movement which is traversed by said part during the resetting operation thereof for preventing such resetting operation, said stop means being automatically retractable as the operator
- 5 manipulates the mechanism to reset the rolls.
54. In a wringer having a frame and spring means for exerting pressure upon the wringer rolls, latch means for releasably maintaining said spring means in pressure applying condition including a member pivotally mounted on said frame, said latch means being normally insufficient alone to resist the pressure exerted by the spring means, holding means engageable with said member to maintain said latch means
- 10 against movement by said spring means, and means movable upon disengagement of said holding means from said member into a position for preventing accidental reengagement therebetween.
55. A wringer comprising, in combination, wringer rolls mounted for separating movement, means by which said rolls are releasably held in operative relation under spring pressure, and means for releasing the holding means to permit separation of said rolls including means to be moved by the operator and located on opposite sides of said rolls to extend crosswise of the rolls adjacent to the ends and across the bite of the latter, and actuating means extending from one
- 15 of the oppositely located means to the other and having an operating connection with said holding means.
56. A wringer comprising, in combination, a frame having a base, channeled side members and a separable head supported by said side members, means for applying pressure to said wringer rolls only when said head is operatively associated with said side members, means for detachably connecting one end of said head with
- 20 the frame including a latch pivotally mounted on said base at the lower end of the side member associated with that end of the head, latch cooperating means connected with said head and extending through the channel of said associated side member for engagement by said latch, means responsive to the manipulative movements of the operator for releasably holding the latch in such engagement, and means for detachably connecting the other end of said head to said frame.
57. A wringer comprising, in combination, a frame member having a base and channeled side members, wringer rolls journaled in said side members, a separable head supported by said members, means for applying pressure to said wringer rolls when said head is operatively associated with said frame member, and means for detachably connecting said head to said frame including a latch pivotally mounted on said base below one of said side members, latch cooperating means connected with said head to extend through the associated side member for engagement with said latch when said head is operatively associated with said side member, means for normally holding said latch in such engagement, and means for effecting engagement of said latch and said cooperating means in the operation of assembling the head on the frame.
58. A wringer comprising, in combination, a frame having separable sections, wringer rolls journaled in said frame, means for applying
- 25 pressure to said wringer rolls when said frame sections are operatively connected, and quickly releasable means for connecting said sections to maintain the wringer rolls under pressure or to release the pressure from said rolls and including an impositive latch on one of said sections, a cooperating member on the other of said sections engageable with said latch, means for effecting engagement between said latch and said cooperating member in the movement of said frame sections into assembled relation, and means for releasably holding said latch engaged with said cooperating member.
59. In a wringer, the combination of a frame section having a base and channeled side stiles, a head adapted telescopically to receive the upper ends of said stiles, rolls journaled in said side stiles and having means associated therewith for applying an operating pressure when the frame and head are assembled, interengaging means for detachably connecting one side stile and the head, means carried by the other end of the head to extend inwardly through the associated side stile to a point opposite said base, an impositive latch mounted on said base for engagement with said means to hold the frame and head assembled, means detachably connected with said latch for maintaining the latch against releasing movement, and means manipulable by the operator for freeing the latch for releasing movement including connected impact members disposed on opposite sides of the frame for movement toward and away from the frame, and a reciprocable bar interposed between said impact members for movement therewith.
60. In a wringer, the combination of a frame section having a base and channeled side stiles, a head adapted telescopically to receive the upper ends of said stiles, rolls journaled in said side stiles and having means associated therewith for applying an operating pressure when the frame and head are assembled, interengaging means for detachably connecting one side stile and the head, means carried by the other end of the head to extend inwardly through the associated side stile to a point opposite said base, an impositive latch mounted on said base for engagement with said means to hold the frame and head assembled, means detachably connected with said latch for maintaining the latch against releasing movement, and means manipulable by the operator for freeing the latch for releasing movement including an impact member disposed on one side of the frame for movement toward and away from the frame, and a reciprocable bar connected with said impact bar for movement therewith.
61. A wringer comprising, in combination, a frame, wringer rolls normally maintained under operative pressure, mechanism for relieving the rolls of such pressure including a reciprocable member mounted for movement transversely of said frame and having a normal central position when the mechanism for relieving the rolls is in set condition, actuators for said mechanism comprising a U-shaped member disposed on each side of the frame with the sides thereof extending downwardly along the sides of the frame, means for connecting said members together for conjoint movement, and means for mounting said members on the frame, said actuators being connected with said reciprocable member for imparting movement thereto as said actuators are moved by the operator.
62. A wringer having, in combination, a frame,

wringer rolls mounted therein for separating movement, means by which said rolls are releasably held in operative position under spring pressure including an unstable latch device and holding means for maintaining said unstable latch device against releasing movement, and means for releasing the holding means to permit separation of said rolls including means to be moved

5 by the operator and located on opposite sides of said frame adjacent to said rolls, and actuating means extending from one of the oppositely located means to the other and having an operating connection with said holding means. 5
